SELF-CLEANING HUMIDIFIER

Agnew H. Bahnson, Jr., Winston-Salem, N. C., assignor to Wachovia Bank and Trust Co., Winston-Salem, N. C., a corporation of North Carolina, as trustee

Application March 16, 1951, Serial No. 215,919

17 Claims. (Cl. 261—90)

1

This invention relates to humidifiers and particularly to humidifiers of the type wherein water is supplied to a rapidly rotating impeller disk from which it is thrown by centrifugal force against a grid ring having a row of stationary blades or teeth circumferentially surrounding the path of the periphery of the disk and thus atomized to be entrained by a stream of air blown past the humidifier.

In known humidifiers of this type, which generally comprise a motor, a motor shaft, a disk mounted on the shaft, a water supply to the surface of the disk near its axis, a grid ring having an annular row of teeth surrounding the disk and an imperforate bowl-like casing peripherally surrounding the blades or teeth, certain difficulties have been encountered in the operation of the devices due to the collection of lint, dirt, etc., on the grid ring. In the case of a humidifier operated in a room wherein there is an appreciable amount of lint in the air, such as in a textile mill, the lint is drawn into the air stream and is deposited on the rim of the casing and on the grid ring where it collects moisture and, due to the passage of the air, extends in the direction of the airstream in elongated tassels or "whiskers." Moisture which is deposited on these tassels by the passage of the moisture-laden air and/or by drainage from the casing, is blown from the collected lint in the form of drops which injure the materials being manufactured. Similar undesirable effects result from the formation of drops on the lint which is caught by and collected on the grid ring.

U. S. Patent No. 1,966,872, issued July 17, 1934, discloses a humidifier structure wherein the formation of stringy, tassel like deposits of large amounts of lint or other foreign matter on the rim of the casing is rendered impossible. Humidifiers of the general type with which the invention is concerned are disclosed also in U. S. Patents Nos. 1,544,418 and 1,745,239 to Bahnson.

It is an object of the present invention to provide a humidifier structure which is adapted to prevent the accumulation of lint and dirt and the formation of tassels or whiskers on the grid ring, e. g. the teeth thereof.

It is a further object to provide a self-cleaning humidifier capable of automatically cleaning the teeth of its grid ring at all times when not acting in its atomizing capacity. Other objects of the invention include provision of a rotatable grid ring, means for rotating said ring when the humidifier is not in atomizing operation, and means for terminating rotation of the grid ring

upon commencement of the atomizing operation.

The invention may be described in brief as follows: It consists of a humidifier having driving means, a water supply system, a rotatable impeller disk, and a rotatable grid ring which is normally stationary. Grid rings ordinarily are mounted to be permanently stationary, but in the present apparatus, the grid ring is designed for rotation at certain times for cleaning. The apparatus preferably is designed to impart rotary motion for cleaning of the grid ring only during those periods in which the humidifier is not acting in an atomizing capacity.

The supply of water to humidifiers of the type with which the invention is concerned normally is intermittent, being controlled in accordance with requirements as established by the relative humidity of the air being conditioned. In the present apparatus, rotation of the grid ring for the cleaning operation is made depend upon the termination of the supply of water from its source, and upon commencement of water supply again, the grid ring becomes stationary. A feature of the invention comprises means for allowing completion of the cleaning cycle of the grid ring after commencement of water supply from the source but prior to admittance of water to the surface of the rotary impeller disk.

Therefore, in the normal operation of the apparatus of the invention, a motor drives the impeller disk continuously and the grid ring is driven intermittently, such as through a transmission from the motor shaft, inclusive of a clutch.

Means mounted on the grid ring serves also to clean the deflector or casing when the grid ring rotates.

The invention is illustrated in the accompanying drawings, in which:

Fig. 1 is a front elevation, in part cut away and in part in section, showing a humidifier embodying the invention.

Fig. 2 is a vertical axial section on the line 2—2 of Fig. 1.

Fig. 3 is a side elevation in part in section, of a portion of the apparatus of Fig. 1.

Fig. 4 is a horizontal axial section on the line 4—4 through a portion of the apparatus of Fig. 1.

Fig. 5 is a section on the line 5—5 of Fig. 4, and

Fig. 6 is a section taken on the line 6—6 of Fig. 4.

Referring to the drawings, 10 is a casing for deflection of an air stream passing to the humidifier, the air stream direction being from right to left with respect to the apparatus illustrated

in Fig. 2. A main shaft 11, receiving power from any suitable source such as a motor 12, drives a rotary water impeller 13 fixed to the shaft. A water supply system having a chamber 14 connected with an inlet feed line 15 from a source of water under pressure and an outlet line 16 supplies water to the surface of a spacer 17 from which the water flows onto the inner surface of the disk near the axis of the latter. Centrifugal force created by rapid rotation of the disk causes the water to move from the center of the disk to its outer edge and to be thrown from the edge against a grid ring 18 having an annular row of teeth 19 which atomize the water by breaking it up into a fine mist or spray which can be carried away by the air stream supplied to the humidifying apparatus.

When the humidifier is in operation, the motor driving the rotary impeller disk may be run continuously, but in accordance with normal procedures water will be supplied to the disk only when the relative humidity of the air being conditioned falls below the desired value. A main valve 20 controls the supply of water whereby feed to the humidifier can be discontinued when the air under treatment contains the required amount of moisture and can be recommenced when it is necessary to again humidify the air. For the purpose of automatic operation of the main valve 20, it is illustrated in Fig. 1 as being under the control of a humidity responsive device such as any of the well known types of humidists commonly available.

The grid ring 18 is rotatably mounted and by an arrangement to be presently described, is held stationary while water is being fed to the impeller during atomizing operations, but is rotated by means of a reduced speed power transmission when the humidifier is not operating as an atomizer.

The reduced speed power transmission includes a worm gear 21 mounted on the main shaft 11 meshing with a gear 22 fixed to a stub shaft 23 journaled in bosses 24 and 25 (carried by a gear box 26 mounted directly behind the grid ring 18). The stub shaft 23 carries a worm gear 27 which meshes with a gear 28 of an assembly consisting of the gear 28 keyed to a shaft 29 to which is fixed a smaller gear 30. The smaller gear 30 meshes with a ring gear 31 coaxially surrounding and supported by the main shaft 11. It will be seen that when the humidifier is in operation with the main shaft 11 and rotary impeller disk 13 under continuous drive, the ring gear 31 will be rotating continuously, but at a greatly reduced rate of rotation in accordance with the illustrated gear ratio.

The ring gear 31 is provided with a clutch slot 32 adapted to receive a clutch to be presently described, whereby clutch engagement of the ring gear with the grid ring 18 and rotational drive of the latter is accomplished.

The grid ring 18 includes an annular disk 33, a cam plate 34 fixed thereto, and a clutch ring 35 fixed to the cam plate 34 and having a projecting flange. A cam depression 36 is formed in the cam plate 34, and centered adjacent the depression 36, in the clutch ring, is a clutch slot 37 housing a clutch 38.

The clutch is provided with a clutch pin 39 which projects out through the clutch plate through an elongated slot 37' of smaller area in plan view than the slot 37 in the clutch ring 35 housing the clutch. A spring 40 positioned in the clutch slot 37 of the clutch ring 35 urges the

clutch 38, riding in the clutch slot outwardly toward the ring gear 31. As the ring gear rotates, the urge of the spring 40 normally is opposed by a clutch control assembly, presently to be described, whereby the clutch is held disengaged from the gear ring. In the absence of opposition by the clutch control assembly to the urge of the spring 40, the spring forces the clutch outward against the inner face of the gear ring, and the outer end of the clutch rides against said face as the gear ring rotates, whereby when the gear ring reaches the proper position to bring its clutch slot 32 in alignment with the clutch slot 37 of the clutch ring, the clutch becomes engaged by reason of its outer end moving into the clutch slot of the gear ring. Engagement of the clutch results in rotation of the grid ring, inclusive of course, of its clutch ring, cam plate, annular disk, and teeth.

Disengagement of the clutch is accomplished by means of the clutch control assembly which is stationary relative to the rotating grid ring. The clutch control assembly includes a clutch disengaging linkage having a cam follower 41 which has a projection 42 adapted to cam against the periphery of the cam plate 34 except when the cam plate presents its cam depression 36.

The clutch disengaging linkage also has a lever arm 43 adapted to move the cam follower 41 under influence from a floating pin 44.

As shown more clearly in Figs. 4-6 the clutch being in the "engaged" position, the clutch pin cams against the face of the cam follower as the former during its rotation reaches the position of the latter. If the cam follower 41 is not under influence (to the left in Fig. 4) of the lever arm 43 (the latter being under no influence from the floating pin 44), the cam follower is free to move to the right against the camming action of the 40 clutch pin whereby disengagement of the clutch is not accomplished, and the cam follower normally is urged to the right (Fig. 4) by the springs 45 and 46 whereby in the absence of force from the lever arm 43 the cam follower remains clear of forceful contact with the clutch pin 39.

It will be clear that when opposite conditions exist, that is when forcing movement of the floating pin 44 to the left (Fig. 4) occurs, responsive to a pressure responsive device presently to be described, the floating pin 44 will move the lever arm 43 and consequently the cam follower 41 to the left. Under these conditions, the cam follower, or rather its projection, will ride hard against the periphery of the rotating cam plate 34 until the cam plate reaches the position at which the cam follower enters the cam depression 36 under the urging of the lever arm 43 and against the opposition of the springs 45 and 46. When cam follower 41 moves into the cam depression 36, continued rotation of the grid ring 18 causes camming action between the cam follower 41 and the clutch pin 39 whereby the clutch member 38 is moved to the left in its slot 37 in the clutch ring 35 against the opposition of the clutch spring 40, becoming disengaged from the gear 31 by reason of withdrawal of its outer end from the clutch slot 32 in the ring gear. Upon disengagement of the clutch, the grid ring 18 becomes stationary, the ring gear continuing to rotate as long as the main shaft 11 continues to receive power. Further movement of the grid ring after disengagement of the clutch is prevented by the projection 42 of the cam follower 41. Obviously, with the clutch engaged, disengaging impulses applied to the clutch disengaging assembly

are ineffective to disengage the clutch at all times except when the grid ring rotates to the position necessary to bring the cam depression 36 and clutch pin 39 into alignment opposite the fixed position of the cam follower. For this reason, once rotation of the grid ring has been commenced, a complete revolution will be had before the clutch is brought back to its point of origin, regardless of the disengaging impulses applied to the cam follower.

Clutch disengaging impulses originate in a pressure responsive secondary valve device 14. The latter includes a valve chamber 14' in the water supply line on the discharge side of the main control valve 20, a resilient diaphragm 47 constituting one end wall of chamber 14', a valve stem 48 secured to diaphragm 47 for controlling flow of water through the valve, and a spring 50 urging the left end of the valve stem into closing position upon its seat in the absence of water pressure in chamber 14'. The right end 48' of the valve stem extends through the valve casing for actuating a pivotally mounted clutch control lever 51.

It will be clear from Fig. 1 that when the main valve 20 is opened to a source of water under pressure, the water will enter the valve chamber 14' through the inlet feed line 15, and with the valve 14 closed (as illustrated in Fig. 1) the water pressure will tend to cause outward flexing of the diaphragm 47 with resultant opening of the valve by movement of the valve stem 48 to the right (Fig. 1) and consequently supply water through the outlet line 16 to the rotary impeller disk. Movement of the valve stem end 48' would result in actuation of the clutch control assembly, the first member of which is the lever 51 against one end of which the end 48' of the valve stem bears in opposition to the floating pin 44, the outer end of which rides against the opposite end of the lever 51. In the condition of the apparatus illustrated in Fig. 1, the clutch being in alignment with the cam follower, admission of water to valve chamber 14' therefore would result in disengagement of the clutch under the influence of the cam follower responsive to movement of the lever 51, in turn responsive to movement (to the right in Fig. 1) of the diaphragm and the valve stem. Accordingly, the rotation of the grid ring would be halted and simultaneously water would be supplied to the rotary impeller disk, placing the humidifier in atomizing operation.

Atomizing operation for a period sufficient to satisfy the humidity requirements of the air being treated would then result in closing of the main valve 20 by the humidity responsive valve operator, whereupon termination of water pressure in the chamber 14' and the influence of the spring 50 would cause return of the diaphragm to its normal position as illustrated in Fig. 1 with consequent closing of the valve 14' and termination of the atomizing phase of the operating cycle of the humidifier. The main shaft 11 still rotates however under drive from the motor 12 and the cleaning phase of the operating cycle would now commence. Since the valve stem end 48' would then be in its left-most position (Fig. 1), lever 51 would be free to move to the position of Fig. 1 under influence from the cam follower springs 45 and 46. Consequently when continued rotation of the ring gear 31 resulted in alignment of its clutch slot 32 with the clutch slot 37 of the clutch ring 35 attached to the stationary grid ring, the clutch 38 would be

moved into engagement under the force of its spring 40 and rotation of the grid ring 18 would begin.

Mounted upon the stationary casing 10 is a grid cleaning device which in the embodiment illustrated in Figs. 1 and 2 comprises a brush 52 which bears against the grid teeth 19. As the grid ring 18 rotates during the cleaning phase, brush 52 serves to sweep and clean the teeth of the grid ring as the grid ring moves past the brush. A second brush 53, mounted on the periphery of the grid ring bears against and serves to clean the lip of the stationary casing as the grid ring and brush rotate within the casing.

The cleaning phase of the humidifier, i. e. relative motion between the brush 52 and grid teeth 19 would then continue until the humidity responsive valve 20 reopened due to the drop in humidity of the space to be controlled whereupon water would then again be admitted to valve chamber 14. However due to the interlocking action between the valve stem 48 and the clutch mechanism, conversion of the water pressure applied to diaphragm 47 into movement of valve stem 48 to the right from the position shown in Fig. 1 to thereby open the valve and permit water to flow through outlet pipe 16 to the impeller 13 for producing the humidifying spray cannot take place until the rotating ring gear 31 and the grid ring assembly have as previously explained moved into the one position where the clutch is disengageable. When such position is reached the valve stem end 48' is free to move pivoted clutch lever 51 clockwise causing rod 44 to shift to the left and disengage the clutch thus bringing the grid ring to rest and simultaneously opening the valve to admit water to the impeller to thereby recommence the humidifying phase.

In conclusion it is to be understood that while the illustrated embodiment is to be preferred, various minor changes in the construction and arrangement of component parts thereof may be made without however departing from the spirit and scope of the invention as defined in the appended claims.

I claim:

1. A self-cleaning humidifier comprising an impeller for distributing water delivered thereto, a grid ring member disposed adjacent said impeller for atomizing water distributed by said impeller, cleaning means cooperative with said grid ring member, means mounting said grid ring and cleaning means for relative rotation, humidity controlled means effecting periodic delivery of water to said impeller, and means effecting relative rotation between said grid ring and cleaning means in the intervals between successive delivery periods of water to said impeller.

2. A self-cleaning humidifier comprising an impeller for distributing water delivered thereto, a grid ring disposed adjacent said impeller for atomizing water distributed by said impeller, a stationary cleaning means cooperative with said grid ring, humidity controlled means effecting periodic delivery of water to said impeller, and means effecting rotation of said grid ring in the interval between successive delivery periods of water to said impeller.

3. A self-cleaning humidifier comprising an impeller for distributing water delivered thereto, a grid ring member disposed adjacent said impeller for atomizing water distributed by said impeller, cleaning means cooperative with said grid ring member, means for rotating said impeller continuously during operation of said

humidifier, means mounting said grid ring and cleaning means for relative rotation, humidity controlled means for delivering water periodically to said impeller, and means effecting relative rotation between said grid ring and cleaning means in the intervals between successive delivery periods of water to said impeller.

4. A self-cleaning humidifier comprising an impeller for distributing water delivered thereto, a grid ring disposed adjacent said impeller for atomizing water distributed by said impeller, a stationary cleaning device cooperative with said grid ring, means for rotating said impeller continuously during operation of said humidifier, humidity controlled means for delivering water periodically to said impeller, and means effecting rotation of said grid ring in the intervals between successive delivery periods of water to said impeller.

5. A self-cleaning humidifier comprising a motor, an impeller secured to the drive shaft of said motor for distributing water delivered under pressure to said impeller, a grid ring member disposed adjacent said impeller for atomizing water distributed by said impeller, a cleaning member cooperative with said grid ring member, one of said members being stationary and the other rotatable, and clutch means for coupling the rotatable one of said members to said drive shaft.

6. A self-cleaning humidifier as defined in claim 5 wherein said grid ring member is rotatable and said cleaning member is stationary.

7. A self-cleaning humidifier as defined in claim 5 wherein said cleaning member is stationary, said grid ring member is rotatable, and further including means limiting operation of said clutch means to a predetermined position of said grid ring member.

8. A self-cleaning humidifier comprising a motor, an impeller secured to the drive shaft of said motor for distributing water delivered to said impeller, a grid ring member disposed adjacent said impeller for atomizing water distributed by said impeller, a cleaning member cooperative with said grid ring member, one of said members being stationary and the other rotatable, a power take off from said drive shaft including a speed reducing transmission, and clutch means for coupling the rotatable one of said members to the output of said transmission.

9. A self-cleaning humidifier comprising an impeller member for distributing water delivered thereto, a grid ring member disposed adjacent said impeller member for atomizing water distributed by said impeller member, a stationary cleaning device cooperative with said grid ring member, a motor common to both of said members for rotating the same, said impeller member being coupled continuously to said motor, clutch means interposed between said motor and grid ring member, and means responsive to the pressure of said water for controlling said clutch means.

10. A self-cleaning humidifier as defined in claim 9 wherein said water pressure responsive control means is comprised of a valve through which said water is delivered to said impeller member, a valve operator responsive to said water pressure, and means controlling said clutch means in accordance with the position of said valve operator.

11. A self-cleaning humidifier as defined in claim 9 wherein said water pressure responsive control means is comprised of a valve through

5 which said water is delivered to said impeller member, said valve including a diaphragm responsive to the water pressure and a valve stem actuated by said diaphragm, and means controlling said clutch means in accordance with the position of said valve stem.

12. A self-cleaning humidifier comprising an impeller for distributing water delivered thereto under pressure, a grid ring member disposed adjacent said impeller for atomizing water distributed by said impeller, a cleaning member cooperative with said grid ring member, one of said members being stationary and the other rotatable, a motor for driving said impeller, a clutch means interposed between said motor and the rotatable one of said members, valve means normally closed but openable under pressure of said water for controlling delivery of said water to said impeller, and means controlling operation of said clutch means in accordance with the operation of said valve means to effect engagement of said clutch means when said valve means is closed and disengagement thereof when said valve means is opened.

13. A self-cleaning humidifier comprising an impeller for distributing water delivered thereto, a grid ring member disposed adjacent said impeller for atomizing water distributed by said impeller, a cleaning member cooperative with 30 said grid ring member one of said members being stationary and the other rotatable, said impeller being coupled to said motor continuously during operation of said humidifier, humidity controlled means for delivering water periodically to said impeller, clutch means interposed between said motor and the rotatable one of said members, and means actuating said clutch means to couple said rotatable member to said motor during the intervals between successive delivery periods of water to said impeller.

14. A self-cleaning humidifier comprising a motor, an impeller driven by said motor for distributing water delivered thereto, a rotatable grid ring disposed adjacent said impeller and mounted coaxially therewith for atomizing water distributed by said impeller, a stationary cleaning device cooperative with said grid ring, a cam plate and clutch ring secured to and mounted coaxially with said grid ring, said cam plate having a depression in the periphery thereof and said clutch ring having a clutch member aligned with said depression and movable radially of said ring, a ring gear driven by said motor, said ring gear being arranged coaxially with said clutch ring and including a slot for receiving said clutch member thereby to couple said gear and ring, and a cam follower cooperative with the periphery of said cam plate and adapted to actuate said clutch member.

15. A self-cleaning humidifier as defined in claim 14 and which further includes valve means responsive to water pressure for controlling delivery of water to said impeller, and means linking said valve means to said cam follower for actuation of the latter by the former.

16. A self-cleaning humidifier comprising an impeller for distributing water delivered thereto, a grid ring member disposed adjacent said impeller for atomizing water distributed by said impeller, cleaning means cooperative with said grid ring member, means mounting said grid ring and cleaning means for relative rotation, humidity controlled means effecting periodic delivery of water to said impeller, and means ef-

fecting relative rotation between said grid ring and cleaning means.

17. A self-cleaning humidifier comprising an impeller for distributing water delivered thereto, a grid ring member disposed adjacent said impeller for atomizing water distributed by said impeller, cleaning means cooperative with said grid ring member, means mounting said grid ring and cleaning means for relative rotation, humidity controlled means effecting periodic delivery of water to said impeller, and means effecting relative rotation periodically between said grid ring and cleaning means.
